UNITED STATES PATENT OFFICE.

RUDOLF PFENNINGER, OF BELLEVILLE, WISCONSIN.

PANIC-PROOF DOOR.

1,187,088.

Specification of Letters Patent. Patented June 13, 1916.

Application filed April 28, 1915. Serial No. 24,605.

To all whom it may concern:

Be it known that I, RUDOLF PFENNINGER, a citizen of the Republic of Switzerland, residing at Belleville, in the county of Dane 5 and State of Wisconsin, have invented a new and useful Improvement in Panic-Proof Doors, of which the following is a specification.

My invention relates to improvements in 10 door constructions, and the object of my invention is to provide a form of door especially suitable for use in theaters, schools, and other public buildings, and characterized by the facility and certainty with which 15 it may be opened in case of panic.

More particularly, it is the object of the 20 invention to provide a form of door which will be rigidly held in closed position, but by the operation of its handle members may readily be opened to swing in either direction and from pintles on either of its two longitudinal edges.

Specifically, it should be noted that it is 25 the object of the invention to provide such a hinge and locking mechanism and operating means therefor as to insure the opening of the door, whether the operating lever or handle be turned in one direction or the other, or whether the door be pushed or 30 pulled.

It is a further object of the invention to 35 provide, in connection with the hinging and locking mechanism referred to, means by which the door may be readily detached and bodily removed from its frame.

Other objects and advantages of my invention will appear more fully from the following detailed description of one form of door embodying the invention. In this 40 description reference will be had to the accompanying drawings in which—

Figure 1 is a section of a door constructed in accordance with my invention, the door being shown in closed position and mounted 45 in a frame in a building wall, certain parts being shown in elevation; Fig. 2 is an enlarged section of a portion of the door shown in Fig. 1; Fig. 3 is an enlarged section on the line 3 of Fig. 2; Fig. 4 is an enlarged section on the line 4 of Fig. 1, the middle portion of the door being broken out; Fig. 5 is an enlarged detailed section of one of the 50 lower securing bolts of the door taken on the line 5 of Fig. 1; Fig. 6 is an enlarged

perspective view of a securing bolt or pintle, 55 and Fig. 7 is a sectional view on the line 7 of Fig. 5.

Referring more particularly to the drawing, the numeral 10 designates a building wall in which is mounted a rectangular door 60 frame 11 having upper and lower transverse members 12 and 13, respectively.

The door proper of my invention comprises front and rear face members 15 (see Fig. 4), spaced apart by the boards 16 and 65 having their outer longitudinal edges joined by strips 17 which have curved outer faces to permit of the swinging of the door, as will later appear. To secure the door within its frame, I provide combined pintle and 70 fastening members of the form shown in Fig. 6 and comprising bolts 18 which lie within longitudinal hollow sections 19 formed by the spaced front and rear face members 15 and the filler block or board 16 75 and secured and guided within such recess by angular brackets 20 (see Fig. 1). The outer end of each bolt 18 is provided with a squared portion 21 which completely fills and is guided by the walls of the recess 19, 80 each squared portion carrying a pintle 22, the end of which is beveled or curved, as shown at 22'. The bolts 18 are constantly urged outward by means of compression springs 23, which encircle the bolts and are 85 confined between washers 24 pinned thereon, and the central brackets 20.

Secured to the inner end of each of the bolts 18 is a cable member 25 which passes 90 inwardly through the recess 19 and around a pulley or roller 26, which may be shrouded by a frame 27 to prevent the cable from running off. From the pulleys 26 the cables run inwardly through conduits 28 formed by spacing apart the middle filler blocks 16 95 and are secured at their inner ends to the ends of a central rack-bar 29, which is slideable within the conduit 28. Above the rack-bar there is mounted a pinion 30 which is carried by the squared portion 31 of a shaft 100 32 which extends through from one face of the door to the other, and is provided on its ends with operating handles or knobs 33. A lock 34, mounted within the door and below the rack-bar 29, is provided with a locking bolt member 35 which may be engaged with a recess 36 in the lower face of the rack-bar, the locking bolt being adapted to 105

be actuated by a suitable key introduced through key-holes 37 in the two faces of the door.

To receive the pintles 22, the upper and lower transverse frame members 12 and 13 are provided with recesses 38 which are preferably covered by latch plates 39 of convex curvature, as shown in Fig. 5 of the drawing, the material of the frame members being cut away to receive these latch plates. The two latch plates 39 in the bottom member 13 are provided with three slots 40 extending from the central aperture 38', which receives the pintle 22, and the lower pintles 22, which engage these latch plates, carry each an outwardly extending lug 41 (see Figs. 5 and 7), the recess 38 in the frame member or sill 13 being enlarged to permit of the movement of the lug 41 therewithin.

The operation of my improved door is as follows: A key member having been inserted through one of the key holes 37, the lock 34 may be actuated to retract the locking bolt 35 from the recess of the rack-bar, whereby the latter becomes free to move within the conduit 28. If either of the knobs or handles 33 be then rotated, the pinion 30 will move the rack-bar to the right or to the left, depending on the direction of rotation of the knob. In either event one pair of the cables 25 will be pulled through the conduit 28 by the movement of the rack-bar to retract the attached bolts 18, whereby the upper and lower pintles 22 upon one side of the door will be withdrawn from the recesses 38. Pressure upon the door in either direction will then cause the latter to swing about the other pair of pintles 22 as a hinge, the curvature of the longitudinal side strip 17 of the door permitting this motion. Thus, for instance, if the pinion 30 be turned in a clockwise direction, as viewed in Fig. 1, the rack-bar 29 will be moved to the left to retract the bolts 18 upon the right-hand side of the door, and if the door be now pushed it will swing outwardly, or if it be pulled it will swing inwardly, upon the left-hand pintles 22 as hinge members. In like manner if the pinion 30 be turned in a counter-clockwise direction, as viewed in Fig. 1, the rack-bar will be moved to the right to release the left-hand pintles 22 and, accordingly, as the door has been pushed or pulled, it will open, swinging about the right-hand pintles 22 as hinge members. It is, therefore, apparent that any motion or combination of motions which may be attempted will serve effectively to open the door. It is unnecessary for the operator to experiment to determine whether the knob should be turned in one direction or the other, or whether the door should be pushed or pulled, or whether it is to be opened on one side or the other, so long as the knob be turned in any direction and pressure in any

direction be applied to the door, the latter will yield and open. This, I consider one of the primary advantages of my construction since it gives to the door, in the highest degree, the quality of being panic proof.

For purposes of ventilation or for moving very large articles through the door, it may be desirable at times to remove the latter entirely from the door frame. This result may be accomplished in a simple manner with a door constructed in accordance with my invention. By reference to Fig. 7, it will be seen that the slots 40 of the latch plate 39 are located in positions at right-angles to one another, one slot lying parallel to the plane of the door so that the lug 41 may pass outwardly therethrough to release the pintle 22 when the door is in a closed position, and the other two slots 40 permitting the pintle to be released from its recess when the door is swung to a full open position in either direction. If, therefore, after the door has been opened, the pinion 30 be rotated in the proper direction, the pintles 22 which serve as hinge members may themselves be withdrawn from the recesses 38, and the door may be bodily removed from the frame. At the same time, the latch plates 39 will prevent such disengagement of the hinge pintles at intermediate positions of the door, so that it will be impossible for the door to become accidentally released when in the act of swinging.

Due to the convex curvature of the latch plates 39 and the corresponding curvature of the ends 22' of the pintles 22, the door may be pushed to the closed position without operating the knob 33, the curved surfaces 22' and 39 acting to force the bolts inwardly as the door is swung closed. It may also be noted that if the pinion 30 be provided with teeth upon a part of its circumference only, the cables 25 may be relieved of all undue strain such as might be set up by an attempt to turn the knob beyond its proper position, such turning being prevented by an engagement of the uncut surface of the pinion with the rack-bar.

While I have shown and described in considerable detail one specific embodiment of my invention, it is to be understood that such showing and description is illustrative only and for the purpose of making my invention more clear, but I do not regard my invention as limited to the particular features of construction shown or described, nor to any of them, except in so far as I have included such limitations within the terms of the following claims, in which it is my intention to claim all novelty inherent in my invention as broadly as is possible in view of the prior art.

What I claim is:—

1. In a door construction, in combination, a door frame, a door mounted therein, pivot

bolt connections yieldingly held in closed position between the door and frame at both the top and bottom of both side edges of the door whereby the door may swing about either 5 side edge and in either direction, a common operating means centrally disposed in said door, and intermediate connections between said means and all of said pivot bolt connections comprising a pinion, a rack in mesh therewith adapted to be moved a limited amount in either direction and flexible connections between the rack and the several pivot bolts whereby movement of the rack in one direction will release one pair of pivot 10 bolts without affecting the other.

2. In a door construction, in combination, a door frame, a door mounted therein, pivot bolt connections yieldingly held in closed position between the door and frame at both 15 the top and bottom of both side edges of the

door whereby the door may swing about either side edge and in either direction, a common operating means centrally disposed in said door, and intermediate connections between said means and all of said pivot bolt connections comprising a pinion, a rack in mesh therewith adapted to be moved a limited amount in either direction and flexible connections between the rack and the several pivot bolts whereby movement of the rack in one direction will release one pair of pivot 20 bolts without affecting the other, and means associated with the door frame adapted to permit a complete removal of the door when said door is in a predeter- 25 mined open position.

RUDOLF PFENNINGER.
